CLAIM

The ornamental design for a lotion dispensing bottle, as shown and described.

DESCRIPTION

FIG. 1 is a perspective view of a lotion dispensing bottle showing our new design;
FIG. 2 is a left side elevational view thereof, the undisclosed opposite side being a mirror image;
FIG. 3 is a front elevational view thereof;
FIG. 4 is a rear elevational view thereof;
FIG. 5 is a top plan view thereof;
FIG. 6 is a bottom plan view thereof;
FIG. 7 is a perspective view thereof, shown without the dispenser for clarity of illustration;
FIG. 8 is a side elevational view of FIG. 7, the undisclosed opposite side being identical;
FIG. 9 is a front elevational view of FIG. 7, the undisclosed opposite side being identical;
FIG. 10 is a top plan view thereof; and,
FIG. 11 is a bottom plan view thereof.
